ASSIGNORS TO HOLORIB, INCORPORATED, OF CLEVELAND, OHIO, A CORPORATION
OF OHIO.

BUILDING CONSTRUCTION.

Application filed January 16, 1924. Serial No. 686,493.

To all whom it may concern:

Be it known that we, (1) JAMES F. LOUCKS, (2) HARRY GILLETT, citizens of the United States, residing at (1) Cleveland, (2) Gates Mills, in the county of Cuyahoga and State of Ohio, have invented a certain new and useful Improvement in Building Constructions, of which the following is a full, clear, and exact description, reference being had to the accompanying drawings.

This invention relates to building constructions and more particularly to constructions embodying sheet metal units, and which units are adapted, when assembled to produce a light but strong metal foundation for walls, roofs, floors, etc.

It is the general purpose and object of the invention to provide a construction unit, of the character referred to, which will allow walls, roofs, floors, etc. embodying sheet-metal foundations to be produced at a relatively low cost; to provide a construction which will enable the units to be assembled quickly and conveniently in a manner analogous to shingling, or weather-boarding, and with the preservation of leak-proof joints; also to provide an extremely strong construction of the sheet-metal structure, as well as a structure so formed as will enable it to afford an efficient support for sheets of insulating, cementitious or fibrous material.

A further object of our invention is to provide a building construction which, when employed for the production of roofs, will enable us to provide roofs combining minimum weight with adequate strength and high-insulating qualities.

We accomplish the foregoing general objects and other and more limited objects which will appear hereinafter by means of the constructions shown in the drawings forming part hereof, wherein Fig. 1 represents a perspective view of a portion of one of the sheet metal units; Fig. 2 a transverse sectional detail of a building construction embodying such units; Figs. 3, 4 and 5, are views, similar to Fig. 2, showing modifications of the invention disclosed in Fig. 2; Figs. 6 and 7 are details in perspective showing a manner in which the sheet metal units may be assembled in overlapped or shingled relation in the direction of the ribs; and Fig. 8 a view, similar to Fig. 7, of a modifi-

cation of the end connection shown in the 55 former view.

Describing the various parts by reference characters, 1 denotes one of our units, the same consisting of a flat sheet of metal provided with hollow ribs 2 projecting from one face thereof, each of the ribs being substantially triangular in section, with its base 2^a remote from the body of the sheet and connected to such body by the convergent sides 2^b, the sides forming an acute angle 65 with each other and preferably meeting at the closed seam 3. The metal sheet 1 may, if desired, be given a coating of lead or other material rendering it capable of resisting acids and other corrosive agents. The 70 metal employed for the sheet 1 is preferably of a gauge capable of being shaped by means of rolls, it being noted that, because of the peculiar shape and the number of the ribs, a flat continuous unit can be made from metal as light as 26-gauge and yet be capable of withstanding all of the ordinary incidents of use in connection with flooring, 75 roofing, etc., even where the material supported by such sheet has practically no inherent strength. As actually constructed, the sheets 1 have been provided with ribs 2 of such depth, by the rolling operation, that the width of the sheet is reduced thereby 80 from 26 inches to approximately 16 inches, 85 with only five ribs to the sheet, the distance between the bases of the ribs being much greater than the widths of such bases.

It will be noted that one edge of the sheet constituting the unit 1 is provided with a flange 4 projecting at substantially right angles therefrom and at its opposite side with a short flange 5, adjacent to a rib 2 and shown as extending in substantially the plane of the sheet; also that the distance 90 between the flange 4 and the adjacent rib 2 is approximately the distance between the centers of two adjacent ribs. The purpose 95 of this will be clear in connection with Fig. 2, wherein two unit sheets 1 are shown assembled side by side, the flange 4 of one unit being inserted into the seam 3 between the sides 2^b of the side rib of the adjacent sheet or unit, the edge of the right hand sheet or unit resting upon the flange 5 of the left hand sheet or unit. The ribs 2 are preferably spaced equidistantly, the distance of the flange 4 from the rib nearest thereto being 100 105

preferably equal to the distance between the centers of adjacent ribs. This, with the arrangement of the rib at the opposite edge of the sheet insures equidistant, or symmetrical, spacing of the ribs throughout an assembly of sheets or units.

In Fig. 2, our invention is shown combined with a sheet or layer of insulating material in such manner as to be particularly useful for roofing or flooring purposes. In this view, 6 denotes one of a number of supports, extending transversely of the ribs 2, on which such ribs may rest. The supports 6 may be joists or roof purlins. In either event, the area desired to be protected is covered by applying the sheets 1 to the members 6. A convenient way of so applying them is by nailing through the ribs 2 into the members 6 at suitable intervals, as indicated at 7, the heads of the nails resting on top of the metal on each side of the seams 3. When a course has been completed by assembling side by side a sufficient number of the sheets or units 1, the next succeeding course of sheets or units may be assembled with the one just laid by overlapping the ends of the sheets of one course upon the ends of the corresponding sheets of the other course. For instance, in the case of a roof, the bottom transverse course will be laid across the purlins, as indicated in Fig. 2. The upper ends of the ribs 2 will be shaped in the manner shown in either Figs. 7 or 8. In Fig. 7, the seams 3 are opened up at what will be the upper end of the course, providing a slot, indicated at 3^a. The lower end of each rib 2 of the next upper course may be narrowed, as shown in Fig. 6, namely, by bending the wall 2^a toward the body of the sheet and by crimping the sides 2^b toward each other. In Fig. 6, the wall 2^b, as thus constricted in width and folded upon itself, is indicated at 2^c. This provides a narrow extension at one end of each rib 2, which narrow extension is adapted to be fitted easily into the slot 3^a at the upper end of the next lower course.

In Fig. 8, we show how this manner of "shingling" or overlapping sheets of successive courses may be accomplished without the necessity for altering one of the ends of each rib 2. As will appear from this view, one end portion of each rib 2 is provided with parallel walls, indicated at 2^d, thereby providing at such end a widened slot 3^b into which widened slots the ends of the ribs of the adjacent course may be inserted, without alteration thereof, merely by springing them into place.

After the desired area has been covered by the sheet metal units, we apply to the upper or exposed surface of the sheets 1 a coating 8, which may be of sheet cork or other insulating material, such as a more

less heavy fiber sheet made from sugar cane and known to the trade as "Celotex." This sheet 8 of insulating material will be applied to the metal sheets or units 1, as by means of asphalt or other suitable adhesive agent, indicated at 9. Where the material 8 is apt to be affected by weather conditions, a coating 10 of any standard waterproofing material may be applied thereto.

In Fig. 3, there is shown a modification of our invention in which the sheets or units 1 are reversed; that is to say, the ribs 2 are projected upwardly, and the spaces between such ribs are filled with any suitable material, such as fiber, the fiber coating being indicated at 11 and being united to the sheets 1 by adhesive 12. Above the coating 11 is a layer of coating 13, which may be sheet cork, "Celotex," or other suitable insulating material, while the whole may be provided with a coating 14 of water proof material. In this case, the sheet is shown as nailed directly to the supporting joists or purlins by means of the nails 7. When desirable, a coating or layer 15 of fireproof material, such as asbestos felt, will be applied to the underside of the metal sheets or units 1, by means of a suitable adhesive 16.

In Fig. 4 there is shown another form of our invention in which a single thick layer 11^a is applied to the metal sheets 1, extending above the ribs 2. Cement may be employed for this covering or layer, instead of cork or fibrous material, in which case no waterproofing will be necessary if the unit is not exposed to the weather. Where cement is used for the covering or coating, the shape of the ribs 2 insures a most efficient bond between the same and the sheet 1. When this form of our invention is used for roofing or other exposed coverings, a coating 17 of waterproofing material will be applied thereto.

In Fig. 5, there is shown substantially the same embodiment of our invention as is illustrated in Fig. 4, except that the sheets or units 1 are applied to the vertical structural beams 18 of a building, being shown as riveted to the flanges of such beams, by means of the rivets 19.

One of the great advantages of our invention is that the sheet metal unit is capable of being produced by the operation of rolls; we have made such units from ten to twelve feet in length and approximately 16 to 17 inches wide, the forming of the ribs and the flanges 4 resulting in reducing the width of the sheets from 26 inches to the width stated, the ribs being approximately three-fourths inch deep, such depth being greater than the width of the base of each rib. By this rolling operation, we are enabled to handle sheets one-eighth inch thick—

of a sufficient thickness to be used for the floors of railroad cars. By reason of the peculiar shape of the ribs, great strength is secured in the sheets or units, the ribs serving as non-collapsible load-sustaining beams or trusses when resting on joists or purlins, as shown in Fig. 2; and this enables us to employ very light gauge metal for the sheets or units, without the necessity for relying upon the strength of the fireproofing or other material applied thereto.

A further advantage of sheets or units produced in accordance with our invention is that the same are provided each with a continuous flat surface. This continuous, or substantially continuous, surface enables us to use a covering of sheet-insulating material having practically no inherent strength without danger of the same breaking through into the hollow ribs, when subjected to moving weights, as is the case with roofs and floors, and also provides, in a metal sheet of given area, a maximum surface for the application of the asphalt or other adhesive material by which the insulating covering is applied and bonded to such metal foundation sheet.

By making the flange 5 in the plane of the sheet 1, the overlapping edge of the adjacent sheet will be slightly elevated, as indicated in Fig. 2. Where this is undesirable the objection may be overcome by merely shortening the side 2^b carrying the flange 5 so that the overlapping portion of the adjacent sheet will be in the plane of the first sheet.

The closing of the seams 3, as pointed out hereinbefore, insures a substantially continuous surface at one side of each sheet for the application of any desired covering material thereto. Where a coating is applied thereto in a liquid condition, the closing of the seams prevents loss of such coating through flowing into the hollow ribs.

Having thus described our invention, what we claim is:

1. A sheet-metal foundation for roofs and floors having a substantially continuous load-carrying surface and a plurality of spaced hollow triangular ribs projecting from the opposite surface, said ribs each having a depth in excess of the width of the base thereof.

2. A sheet-metal foundation for roofs and floors having a substantially continuous load-carrying surface and a plurality of hollow triangular ribs projecting from the opposite surface, the distance between the longitudinal centers of adjacent ribs being materially greater than the width of the base of a rib.

3. A sheet-metal foundation for roofs and floors comprising a metal sheet having a substantially continuous load-carrying surface, and a plurality of spaced hollow tri-

angular ribs projecting from the opposite surface, each rib having a depth in excess of the width of the base thereof and the distance between adjacent ribs being materially greater than the width of the base 70 of a rib.

4. The combination, with a sheet-metal foundation for roofs and floors having a substantially continuous surface and spaced triangular ribs projecting from the opposite 75 surface and constituting beams for supporting the said foundation, of a sheet of insulating material for the first-mentioned surface and supported at substantially all points thereby, and adhesive material applied to such surface and uniting such insulating material thereto.

5. A building structure for roofs and floors comprising the combination, with supporting beams, of a sheet-metal foundation having a plurality of spaced integral angular ribs extending across said beams and supporting the foundation thereby, said ribs projecting on one side only of the foundation and being substantially closed 90 at their junction therewith, the opposite side of the foundation presenting a substantially continuous load-sustaining surface.

6. In a roof or floor structure, the combination, with supporting members, of a 95 series of sheet metal plates mounted thereon, each plate having integral spaced angular ribs formed on one side only thereof, said ribs extending across the members and forming in effect load-sustaining trusses between the same, the other side of such plate forming a substantially continuous surface, and a covering of insulating material applied to the last mentioned surface and supported at substantially all points thereby.

7. In a roof or floor structure, the combination, with supporting members, of a sheet-metal foundation mounted thereon and having integral spaced angular ribs formed on one side only thereof, said ribs extending across the members and forming in effect load-sustaining trusses between the same, the other side of the foundation forming a substantially continuous surface, and a covering of insulating material adhesively secured to the last mentioned surface and supported at substantially all points thereby.

8. A building structure for roofs and floors comprising a load-carrying metal 120 sheet having spaced hollow triangular ribs formed therewith and projecting from one surface thereof, the side walls of each of said ribs substantially meeting at said sheet and forming an acute angle with each other 125 whereby collapse of the ribs by a covering applied to the opposite surface of the sheet is prevented and such covering is supported at substantially all points by such surface.

9. A building structure for roofs and 130

- 5 floors comprising a load-carrying metal sheet having hollow triangular ribs formed therewith and projecting from one surface thereof, the side walls of each of said ribs substantially meeting at said sheet and forming an acute angle with each other whereby collapse of the ribs by a covering applied to the opposite surface of the sheet is prevented and such covering is supported 10 at substantially all points by such surface, the distance between adjacent ribs being materially greater than the width of the base 15 of a rib.
10. A sheet metal foundation comprising a metal sheet having spaced triangular ribs
- 15 formed therewith and projecting from one side thereof, the sides of the ribs substantially meeting at the sheet whereby the said foundation is provided with a substantially continuous surface on the side opposite the 20 said ribs, each rib being constricted in width at one end for insertion into a rib of an adjacent sheet, whereby said sheets may be assembled and overlapped in shingled condition.
- 25

In testimony whereof, we hereunto affix our signatures.

JAMES F. LOUCKS.
HARRY GILLETT.
